CORRUGATED CLIP FOR SELF-ALIGNING SHINGLES

Robert Hayes, Woodhaven, and Joseph Slater, Ozone Park, N. Y., assignors of two-thirds to Thomas K. Raymond, Forest Hills, N. Y., and one-third to said Hayes

Application February 28, 1941, Serial No. 380,992

4 Claims. (Cl. 108—33)

This invention relates to a corrugated clip for self-aligning rigid side-wall shingles.

More specifically the invention proposes to characterize the clip by a base strip portion formed with an elongated slot for a headed fastening element to frictionally hold the clip, and a hook portion for engaging a shingle and eliminating all face nails.

Furthermore the invention proposes that each shingle be supported by at least two of the clips.

It is proposed that each fastening element pass through the elongated slot of a base strip portion and through a shingle directly below the clip. It is proposed that the fastening element engage into the wall upon which the shingle is mounted. The arrangement is such that when the next uppermost shingle is engaged in the hook portion of the clip it extends over the elongated slot and the fastening element which holds the clip, so as to cover these parts and prevent the weather from passing through.

Still further, the invention contemplates to construct the hook portion of the clip with corrugations to match the corrugations of the shingles, in those cases where the shingles have corrugations.

Still further, this invention contemplates various modified forms of clips provided with elements to further assist in holding them in position when in use.

The invention also proposes the construction of clips as mentioned which are simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a fragmentary elevational view of a group of shingles supported with clips constructed in accordance with this invention.

Fig. 2 is a fragmentary sectional view taken on the line 2—2 of Fig. 1.

Fig. 3 is a perspective view of one of the clips, illustrated per se.

Fig. 4 is a fragmentary enlarged elevational view of a shingle with a support clip constructed in accordance with a modified form of this invention.

Fig. 5 is a fragmentary sectional view taken on the line 5—5 of Fig. 4.

Fig. 6 is a fragmentary sectional view similar to Fig. 5 but showing a different condition of the parts.

Fig. 7 is another fragmentary sectional view similar to Fig. 6 but illustrating a modified construction.

The corrugated clip in accordance with this invention includes a base strip portion 10 having an elongated slot 11, and a hook portion 12 at its bottom end. It is proposed that this clip be used for supporting a bottom of a shingle. A group of these clips are shown in Figs. 1 and 2 supporting a group of shingles upon a wall structure 13. It should be noted that each clip is held in position with a headed fastening element 14 which passes through the elongated slot 11 and through an area of an adjacent shingle and then into the support wall 13. As shown in Fig. 2, the fastening element 14 illustrated in full lines in passing through the shingle 15. The next uppermost shingle 15 is engaged upon the hook portion of the clip, and extends over the head of the fastening element 14 and over the slot 11.

The slot 11 is very useful in properly aligning the shingles, as these parts are being placed in position. It is proposed that each shingle be supported at least by two clips at its bottom edge. It is necessary that the clips be properly aligned to correctly support the shingle. The slots 11 make it possible to shift the clips so that the clips will be properly aligned, since if one or more of the clips are out of line it is a simple matter to hammer the clip or clips upwards or downwards against the frictional holding of the head or heads of the fastening element or elements. After the clips which support one of the shingles are properly aligned, this particular shingle will be permanently secured in position by nailing down the clips for the next shingle and these latter mentioned clips may be properly aligned by forcing them upwards or downwards as the case may require. This is only necessary on the first line of horizontal shingles, each line aligns itself, thereby eliminating unnecessary labor and also simplifying the application of the shingles.

By means of this self-aligning application, all face nails are eliminated and corrugations are provided on the face of the clips to coincide with the design of the shingle.

It is proposed that in the event the shingles are provided with corrugations 16, representing a wood design, or another design, that the end hook portions 12 of the clips be corrugated, as indicated by reference numeral 16', to blend in with the corrugated parts of the shingles. This

may be clearly understood from an examination of Figs. 1 and 3.

In Figs. 4 to 6, modified form of the invention has been disclosed which distinguishes from the prior form in the provision of a washer 18 engaged in the slot 11' of the base strip portion 10' of the clip. This washer 18 is provided with straight sides 18a extending along the sides of the slot 11'. Gripping elements 19, in the form of small prongs or projections are formed upon the straight sides of the washer 18 and engage complementary gripping elements on the sides of the slot 11' to securely lock and keep the parts in position.

In Figs. 4 and 5 the clip is shown supporting the shingles 20 and 21. A headed fastening element 22 is shown engaged through an opening 23 formed in the washer 18 and engaged through the shingle 20 and into the supporting wall 24. The shingle 21 is shown engaged into the hook portion 12 of the clip.

Fig. 6 illustrates the parts before they are in their final positions. Normally the washer 18 is convexed, as illustrated in Fig. 6. When in this position it may be placed into the slot 11'. A fastening element 22 may be driven downwards to partially flatten out the washer 18, until the gripping elements 19 start to interengage. At this point the hammering must be stopped and then the clip properly shifted upwards or downwards so as to align it with the other clips which are to support the shingle 21. When the clip has been properly aligned, the fastening element 22 is completely driven down into position. This will flatten out the washer 18 to the condition illustrated in Fig. 5. In this condition the fastening elements 19 are firmly engaged. This construction will assist in properly supporting the shingles and reducing the danger of the clips becoming loose by the fastening elements loosening in the supporting wall.

In Fig. 7 still another form of the invention has been disclosed which is very similar to the prior form distinguishing in the fact that the fastening element 25 has several downwardly extending piercing elements 26 for engaging through the side portions of the base strip portion of the clip. With this arrangement, when the fastening element 25 is driven downwards into position the piercing elements 26 engage through the side portions of the base strip portion 10 holding them from sliding or bending laterally.

The advantage of this is that the washer 18 may then be flattened, and we are certain that the gripping elements 19 will firmly engage and grip the complementary gripping elements of the base strip portion.

The clips are particularly intended for rigid side-wall shingles made of asbestos or other rigid substance. The advantage in using the clips resides in the fact that any cracks produced in the shingles when the fastening elements are driven into position, will be covered up by the covering portions of the upper adjacent shingles. This arrangement assists in preventing the weather from passing through cracks and openings in the shingles produced by the

fastening elements. It also provides clips which have similar surface ornamentals to the surface design of the asbestos shingles which make the clips less conspicuous.

5 It is to be understood that this device does not increase the lap of these rigid side-wall shingles. In other words, the exposed part of the shingles is not increased or decreased in the standard application of the shingles.

10 While we have illustrated and described the preferred embodiments of our invention, it is to be understood that we do not limit ourselves to the precise constructions herein disclosed and the right is reserved to all changes and modifications coming within the scope of the invention as defined in the appended claims.

Having thus described our invention, what we claim as new, and desire to secure by United States Letters Patent is:

20 1. A clip for rigid side-wall shingles, comprising a base strip portion having an elongated slot for a headed fastening element to frictionally hold the clip, a hook portion on the bottom end of said base strip portion for engaging over an edge of a shingle, and a washer engaged in said slot and having straight sides with gripping elements engaging complementary gripping elements on the sides of said slot.

25 2. A clip for rigid side-wall shingles, comprising a base strip portion having an elongated slot for a headed fastening element to frictionally hold the clip, a hook portion on the bottom end of said base strip portion for engaging over an edge of a shingle, and a washer engaged in said slot and having straight sides with gripping elements engaging complementary gripping elements on the sides of said slot; said washer provided with an opening through which said fastening element passes.

30 3. A clip for rigid side-wall shingles, comprising a base strip portion having an elongated slot for a headed fastening element to frictionally hold the clip, a hook portion on the bottom end of said base strip portion for engaging over an edge of a shingle, and a washer engaged in said slot and having straight sides with gripping elements engaging complementary gripping elements on the sides of said slot; said washer provided with an opening through which said fastening element passes, said fastening element having a head formed with downwardly extending piercing elements for engaging through the side portions of said base strip portion.

35 4. A clip for rigid side-wall shingles, comprising a base strip member having an elongated slot for a headed fastening element to frictionally hold the clip, a hook portion on the bottom end of said base strip member for engaging over an edge of a shingle, a washer member in said slot and having straight sides adjacent the straight sides of said slot, and gripping elements formed on the straight sides of one of said members and engaging the straight sides of the other of said members for holding said members against relative movement.

ROBERT HAYES.

JOSEPH SLATER.
